No. 830,287.

PATENTED SEPT. 4, 1906.

N. BENJAMIN.
RAILROAD TIE.
APPLICATION FILED FEB. 7, 1906.

UNITED STATES PATENT OFFICE

NEWTON BENJAMIN, OF ELMIRA, NEW YORK.

RAILROAD-TIE.

No. 830,287.

Specification of Letters Patent.

Patented Sept. 4, 1906.

Application filed February 7, 1906. Serial No. 299,926.

To all whom it may concern:

Be it known that I, NEWTON BENJAMIN, a resident of Elmira, in the county of Chemung and State of New York, have invented certain new and useful Improvements in Railroad-Ties; and I do hereby declare the following to be a full, clear, and exact description of the invention, such as will enable others skilled in the art to which it appertains to make and use the same.

My invention relates to improvements in railroad-ties, and more particularly to improvements upon the construction disclosed in Patent No. 524,999, granted to me August 28, 1894.

In my patented construction I employ inverted T-rails, with blocks or other devices secured between the rails to support the railroad-rails, and in the present invention I dispense with all necessity for separate supporting devices for the rails and instead provide channel-irons secured back to back, affording a wide base and top to receive the rail without additional supporting mechanism; and the invention consists in certain novel features of construction and combinations and arrangements of parts, as will be more fully hereinafter described, and pointed out in the claims.

In the accompanying drawings, Figure 1 is a plan view illustrating my improvements. Figs. 2 and 3 are views in section, and Figs. 4 and 5 are views of a modification.

1 1 represent channel-irons riveted together at one end and extending back to back for about one-third their length, then flared apart and again extending parallel in straight lines, and having short sections 2 of similar channel-irons securely riveted thereto with back to back of said irons 1 1. These channel-irons 1 and 2 have base-flanges 3 of greater width than their top flanges 4, affording a firm support for the tie, and the top flanges 4 afford a wide support for the rails 5. The top flanges 4 are made with oblong holes to receive the angular portions of bolts 6 and prevent the latter from turning. The bolts 6 have heads 7 at their lower ends bearing against the under side of top flanges 4, and their angular portions also project through oblong holes in plates 8, which latter project over the base-flanges of rails 5 to secure them to the ties, and the upper ends of bolts 6 are

screw-threaded to receive nuts 9 to clamp the plates 8 against rails 5 and firmly secure the rails to the ties. These clamping-plates 8 are preferably located diagonally with relation to each other, so that one plate will be on one channel-iron and one on the other, and hence prevent the cutting of two holes close together in the same channel-iron.

In the modification shown in Figs. 4 and 5 a straight channel-iron 10 is shown having short sections of channel-iron 11 secured to its flat or back side at its ends, and the base-flange of this channel-iron 10 may be cut away at its central portion to avoid possibility of the tie binding in the center. The preferred form of my invention might also be provided with cut-out portions for this purpose and a great many other changes might be made in the general form and arrangement of the parts described without departing from my invention. Hence I do not restrict myself to the precise details set forth, but consider myself at liberty to make such slight changes and alterations as fairly fall within the spirit and scope of my invention.

Having fully described my invention, what I claim as new, and desire to secure by Letters Patent, is—

1. A railroad-tie comprising a channel-iron member of sufficient length to extend under both rails of a track, and a shorter channel-iron member to be disposed under one of the rails of a track, said channel-iron members secured together back to back.

2. A railroad-tie, comprising two channel-irons secured together at one end, flared apart at their other ends, and short sections of channel-irons secured to the flared ends of the first-mentioned channel-irons.

3. A railroad-tie, comprising two channel-irons secured together at one end, flared apart at their other end, short sections of channel-irons secured to the flared end of the first-mentioned channel-irons, and all of said channel-irons having wider flanges at their base than at the top.

In testimony whereof I have signed this specification in the presence of two subscribing witnesses.

NEWTON BENJAMIN.
